UNITED STATES PATENT OFFICE

2,585,888

KNITTED FABRIC

George Henry Woolley, Woodside, England

Original application December 24, 1946, Serial No. 718,156, now Patent No. 2,529,207, dated November 7, 1950. Divided and this application February 18, 1948, Serial No. 9,151. In Great Britain June 1, 1945

4 Claims. (Cl. 66—201)

1

This invention is for improvements in knitted fabrics and has particular reference to intarsia or argyll patterns. Intarsia fabric or split work is weft knitted fabric composed of a plurality of different weft yarns which are substituted one for another at predetermined intermediate points in each or certain of the courses so that a given course consists of a predetermined number of stitches of one yarn followed by a predetermined number of stitches of another yarn without the withdrawn yarn floating behind the yarn substituted for it. An object of the invention is to improve the appearance of such patterns.

It is already known to provide fabric incorporating a series of diamonds and to knit an embroidery thread over the diamonds to produce well known argyll patterns. Heretofore however the fabric at the junction of each diamond with the next succeeding diamond has been somewhat thick or bulky because at such junction at least one loop and usually two in each course has been composed of two threads (one from each of two adjacent patterns).

An important object of the present invention is to reduce this bulkiness and the invention therefore provides intarsia fabric having at each of selected points whereat the yarns are substituted one for another, a single composite loop of the stitch loops of the different yarns which are located at said point. Conveniently one of said composite loops is formed at each alternate point in each alternate course and another at each of the other alternate points in each of the remaining courses. The fabric may be produced by any suitable straight bar knitting machine employing two carrier rods, each equipped with carriers capable of being traversed in the same direction to supply their threads to the needles in each course and of being shogged simultaneously in opposite directions at the end of the traverse, and having means for shogging one rod through one needle space in one direction and the other rod through two needle spaces in the opposite direction while the carriers are at the back or plain side of the needles. In one example the fabric may be produced by the machine described in the specification of application Serial No. 718,156, filed December 24, 1946, now Patent Number 2,529,207 of which this application is a division.

The foregoing and other features of the invention set out in the appended claims are incorporated in the fabric which will now be described with reference to the accompanying

5 drawing which illustrates a portion of fabric (looking on the rear face thereof) and the carrier movements for producing it.

In the drawings there is shown the narrowed upper part of one diamond flanked by the widened lower parts of two adjacent diamonds; the yarn, of which the first mentioned diamond is composed, is shaded in order to render the diamond visually distinctive. The said diamond is produced by a representative carrier on a rod which, throughout the courses shown, has its traverse progressively reduced and may therefore be termed the narrowing rod. The two flanking diamonds are produced by two of the carriers on the other rod, which, in the courses shown has its traverse progressively increased, and may be termed the widening rod. At the end of each traverse or draw of the rods, the widening rod is shogged through one needle space (to widen the 10 diamonds produced by its carriers) and the narrowing rod is shogged through two needle spaces in the opposite direction (to narrow the diamond produced by its carrier) while the carriers are at the plain side. Thus, for example 15 considering carriers 4a as being widening carriers and carriers 4b as being a representative narrowing carrier it will be seen that in course A, at the end of the traverse to the right the carriers are swung to the plain side of the needles and while the widening carriers 4a are shogged through one needle space in the widening direction the narrowing carrier is shogged through two needle spaces in the narrowing direction. Considering the right hand juncture, as a result 20 of these movements the first needle which 25 knits the yarn from the narrowing carrier 4b in the next course B is spaced two needle spaces inwards (i. e. to the left) of the last needle which 30 knitted said yarn in course A. The loops thus 35 produced are indicated at 30 and 31, loop 30 being a duplex loop knitted of both yarns and loop 31 of one yarn only which latter floats at 32 at the back of the fabric between the two loops. At the end of the traverse to the left in the next 40 course B the narrowing carrier 4b is shogged two needle spaces to the right (in a narrowing direction) while at the back of the needles, while the widening carriers 4a are shogged one needle space to the left (in a widening direction). This 45 results in there being one duplex loop 30' in course B, at the left hand juncture, which is 50 knitted of two yarns. If the carrier traverse is adjusted at every course a duplex loop (30 or 30') appears in each juncture only at every second course and at every second wale, and it

will readily be appreciated that by virtue of the spacing of the duplex loops the joint is much less bulky than if a duplex loop appears in every wale and every course of the juncture.

As previously stated the fabric may be produced by any suitable means but preferably it is produced on the machine described in the U. S. patent application Serial No. 718,156, filed December 24, 1946, now Patent Number 2,529,207 of which this application is a division.

I claim:

1. A flat knit fabric comprising three coursewise adjacent areas each knit of a separate yarn, said areas being joined by sutures which extend at an angle to the wales and courses, the yarn of the intermediate area being knit together with the yarn of one adjoining area in single stitches in alternate courses only and being knit together with the yarn of the other adjoining area in single stitches in intervening courses only, the yarn of said intermediate area being floated across at least one stitch coursewise adjacent one of said single stitches and being drawn through the next coursewise adjacent stitch to form the end stitch in an adjacent course of said intermediate area.

2. A flat knit fabric comprising three coursewise adjacent areas each knit of a separate yarn, said areas being joined by sutures which extend at an angle to the wales and courses, the yarn of the intermediate area being knit together with the yarn of one adjoining area in single stitches in alternate courses only and being knit together with the yarn of the other adjoining area in single stitches in intervening courses only, the yarn of said intermediate area extending, without being formed into a knitted loop, across at least one stitch coursewise adjacent one of said single stitches and being drawn through the next coursewise adjacent stitch to form the end stitch in an adjacent course of said intermediate area.

3. A flat knitted fabric comprising two coursewise adjacent areas, each knit of a separate yarn, said areas being joined by a suture which extends at an angle to the wales and courses, the yarns of said areas being knit together in single stitches in alternate courses only and the yarn of one of said areas being floated across at least one stitch coursewise adjacent one of said single stitches and being drawn through the next coursewise adjacent stitch to form the end stitch in an adjacent course of that area to which said floated yarn belongs.

4. A flat knitted fabric comprising two coursewise adjacent areas, each knit of a separate yarn, said areas being joined by a suture which extends at an angle to the wales and courses, the yarns of said areas being knit together in single stitches in alternate courses only and the yarn of one of said areas extending, without being formed into a knitted loop, across at least one stitch coursewise adjacent one of said single stitches and being drawn through the next coursewise adjacent stitch to form the end stitch in an adjacent course of that area to which said floated yarn belongs.

GEORGE HENRY WOOLLEY.
